UNITED STATES PATENT OFFICE.

FREDERICK W. SEYMOUR, OF FLUSHING, NEW YORK.

VARIABLE PATHWAY.

Application filed October 25, 1923. Serial No. 670,712.

This invention relates to means for transmission, reception, and control of electrical impulses or activities or other forms of wave motions and has particular reference to 5 means constituting what I purposely designate as "pathways", along or across which the impulses may be conveyed, transmitted, or regulated, and distinguished from the more restricted term "circuits" as applied 10 to metallic or other analogous conductors.

Among the objects of the invention is to provide a pathway system for electrical impulses which involves the use of a flexible, relatively thin, pliable body in the nature 15 of insulation and capable of being made to assume various forms or with the different parts thereof in differently related positions, and for the deposition on the surface of said body, or otherwise extended along the same, 20 of a line or strip of metallic or other suitable material, also of thin and pliable physical nature so that it may partake of the same variation in form or position as the body upon which it is placed or formed.

25 Another object of the invention is to provide a system of pathways made variable for the control of electrical impulses or the like, the same embodying one or more relatively flat pliable bodies having formed, preferably 30 by a galvanic deposit, thereon any suitable design, size, or construction of metallic elements adapted for various purposes according to the specific design or arrangement of the mechanism, so that one part of the structure which in normal position may lie in the 35 same plane as another part, may, when the structure is distorted or manipulated, be brought into superimposed position in relation to the other part, or occupy either a 40 plane parallel thereto or a plane at a different angle thereto, or may assume any form or desired position relative to said other part.

45 In the radio reception and transmission of recent times it is the practice of operators to use coils and masses of metal alone or in combination to control the messages and music broadcasted and received, and many of these instruments thus formed are 50 cumbersome and bulky and otherwise poorly designed, all of which conditions depend largely upon control of the inductance or capacity and combinations of the inductance and capacities. In order to afford an improved method of obtaining and varying

these units and their combinations this invention offers new and useful ideas of means made effective by the application of galvanic action to deposit metal upon a pliable insulating material, movement of which material moves the metal parts and varies the units.

Another object of the invention is to provide pathways made up of variable resistance, capacity, inductance and impedance by 60 means of depositing thin layers of metal, such as copper or silver by galvanic action upon a thin sheet of pliable material such as gutta percha, thus having the metal take the form of the pliable material. As the 65 gutta percha sheets are pliable and easily bendable the metal thereupon will be bent or moved with the sheet. As the metal when deposited in thin lines concentrically forms a coil, so also if deposited in masses or in 70 parallel lines comparatively broad, parts of a condenser will be formed. Now by bending a coil the field about it is distorted and made variable; likewise with the condenser when the masses are brought nearer to each 75 other the capacity is changed and so with all parts in combination.

With the foregoing and other objects in view the invention consists in the arrangement and combination of parts hereinafter 80 described and claimed and while the invention is not restricted to the exact details of construction disclosed or suggested herein, still for the purpose of illustrating a practical embodiment thereof reference is had to 85 the accompanying drawings, in which like reference characters designate the same parts in the several views, and in which—

Figure 1 is a plan view of one embodiment 90 of the invention.

Fig. 2 is an edge view of the same in 95 partial or superimposed position, the broken lines indicating a variation in shape of one half of the carrier or body.

Fig. 3 is a plan view of a further variation 100 of the device.

Fig. 4 is an end view of the mechanism of Fig. 3 as rolled into a loose spiral or spiral cylinder.

Referring now more specifically to the 105 drawings, 10 indicates a sheet of pliable material such as gutta percha, waxed paper, or other analogous material commonly regarded as insulation. This body is shown as being composed of two substantially equal rec- 110

tangular parts connected by a relatively narrow neck portion 11, whereby one part may be folded or bent so as to be superimposed upon or above the other as in Fig. 2 or either part may be given a movement in its own plane in a direction approximately parallel to the other part for the variation of the effect of the electrical impulse being manipulated. Also since the body is pliable either part may be distorted into curved, spiral, or cylindrical form suggested in broken lines in Fig. 2, for the purpose of variations of practical effect. It is obvious that various mechanical means may be provided for mounting, supporting, and manipulating these flexible bodies, but for the purpose of this specification it is deemed unnecessary to show such mechanism.

Each of the parts of the body 10 is provided with a slender metallic member 12 indicated as a spiral line of copper deposited thereon by galvanic action. In accordance with the usual practice in the galvano deposit of metals on pliable bodies or bodies of a non-conductive property, I form a pattern on the flexible sheet or support by any well known means such as the placing thereon of lead, graphite, solution of copper, or any other material of a conductive property which constitutes the base or cathode during the galvanic action while in the galvanic bath. It is impossible by any other means to deposit by the galvano process a conductive metal of either high or low or any other resistivity upon an insulating or non-conductive material. In this figure the two coils 12 are indicated as of right and left turn and so designed that one may be superimposed directly upon the other or in close proximity to each other when one body is folded or bent over the other. The outer ends of the coils may be connected in any suitable manner to other parts of a circuit system in a well known manner, and the inner ends of the coils may be connected by a line of similar deposit 13, or otherwise, extending along the opposite side of the body. These deposits in Fig. 2 are exaggerated in thickness but will be understood in practice as being of almost negligible thickness. In Fig. 3 coils 12' are shown, and as a variation from the illustration in the first figure they are shown as of the same character and connected on the same side through a connector 13'. It will be appreciated that the capacity and inductance of a circuit connected through the pathways illustrated herein may be varied in many ways, to effect the increase or decrease thereof according to the nearness or relative positions of the parts of the pathway elements.

At 14 I indicate a deposit element which may be thought of as a condenser having spaced and substantially parallel corresponding arms 15 and 16, the capacity or induc-

tance of the various parts of which may be varied by the flexing of the body upon which these features are placed or deposited or by the superimposition of the condenser over or upon one or the other or both of the 70 coil features of the same embodiment. One part of the condenser is shown connected through a line 17 to one of the coils, such line being on the opposite side of the body.

It will be understood that the illustrations 75 are but a few of the many variations or forms of the generic idea hereinafter claimed as new. For instance, the deposit elements may be in the nature of disks or films of sheet metal or they may partake of many 80 other specific designs according to the nature of the mechanism or use to which they may be put. As indicated for example at 12^a in Fig. 3 the formation of the pathway by galvanic deposit renders it feasible and practicable for the cross section or carrying capacity of the metal part to be varied readily during the construction, a feature that could not be performed by the use of ordinary conducting wires or the like. This formation at 90 12^a may be regarded, for claiming purposes, as a field piece. The nature of galvanic deposition renders the metals of a high degree of purity and makes it feasible for the same to be more readily formed or deposited 95 in lines or layers of different sectional areas or shapes, and composed of metals such as nickel, copper, silver, or gold, either singly or combined in layers or sections.

I claim:

1. In combination, a sheet of pliable insulating material, a deposit by galvanic action of metal in concentric convolutions on said sheet forming an inductance, a similar deposit of metal in strips forming a condenser, and also on said sheet, and a similar deposit of metal on said sheet forming a field piece, all three deposits constituting a correlated flexible and therefore variable electrical pathway.

2. A construction as set forth in claim 1 in which the field piece deposit is interposed between the inductance and the condenser and at the same side of the flexible sheet of insulation.

3. In combination, a body of pliable insulating material having formed thereon by galvanic deposit a pathway comprising three distinct but correlated masses of metal, one of which is a spiral constituting an inductance, another is arranged in strips spaced relatively to one another and forming a condenser, while the third is a field piece composed of masses or formations of metal of different design or shape from those first mentioned, the whole constituting an electric pathway whose function is variable due to the flexibility of the body of insulation and the character of the deposit thereon.

4. A method of constructing electrical ap- 130

- paratus which consists in marking out circuitous paths upon a supporting surface, placing a conductive material over the paths and electroplating the conductive material 5 with a metal having low resistance to radio frequency currents.
5. The method of manufacturing variable electrical apparatus which consists in suitably preparing a pliable insulating body of 10 sheet material, subjecting said body to a galvanic bath, and depositing on said body a slender electrical pathway whose electrical units are rendered variable because of the pliability of the insulating body.
- 15 6. The method of manufacturing variable electrical apparatus which consists in suitably preparing a pliable body of sheet insulating material, subjecting said body to a galvanic bath, depositing on said body a slender variable electrical pathway as a result 20 of the preparation aforesaid and the action of the galvanic bath, and removing the body of sheet material thus formed from said bath.
- 25 7. The method of manufacturing variable electrical apparatus which comprises the subjecting of a pliable body having parts relatively movable to one another into a galvanic bath, forming on said body of an electrical pathway as a result of galvanic action while in said bath, said pathway having portions of variable cross sectional dimensions, and removing the pliable body 30 from the bath.
- 35 8. A spiral variable electrical conductor comprising, in combination, a pliable body of insulating material, and an electrical pathway formed spirally on said body by galvanic action, the electrical units of the spiral pathway being variable as a result of 40 the pliability of said body.
9. A construction as set forth in claim 12 in which different portions of the spiral pathway are of different cross sectional dimension for the purpose of increasing the 45 variability of the device as an electrical apparatus.
10. The herein described electrical device comprising a support of non-conductive material and a galvanic deposit on the surface 50 of said support of a body of conductive material, different portions of which deposited body are of different cross sectional areas whereby variations in inductance and capacity of the body are obtainable at different 55 points of the body.
11. The herein described method of manufacturing an electrical apparatus which consists in suitably preparing a supporting body 60 of insulating material, subjecting said body to a galvanic bath, depositing on said body an electrical pathway of conductive material, and so controlling the depositing action that said pathway will be of different cross sectional areas at certain points than 65 it is at others.
12. The herein described method of manufacturing an electrical apparatus which consists in suitably preparing a supporting body 70 of insulating material, subjecting said body to a galvanic bath, depositing on said body an electrical pathway of conductive material, and controlling the depositing action so that the pathway will be wider at some 75 points than at others.

In testimony whereof I affix my signature.

FREDERICK W. SEYMOUR.
